UNITED STATES PATENT OFFICE.

ALEXANDER F. DEMORY, OF HAGERSTOWN, MARYLAND, ASSIGNOR TO HAGERSTOWN NOVELTY COMPANY, INC., OF HAGERSTOWN, MARYLAND, A CORPORATION OF MARYLAND.

TOOL FOR REMOVING AND REPLACING MILK-BOTTLE CAPS.

1,299,690.

Specification of Letters Patent.

Patented Apr. 8, 1919.

Application filed April 20, 1915. Serial No. 22,615.

To all whom it may concern:

Be it known that I, ALEXANDER F. DEMORY, a citizen of the United States, residing at Hagerstown, in the county of Washington 5 and State of Maryland, have invented a new and useful Tool for Removing and Replacing Milk-Bottle Caps, of which the following is a specification.

This invention relates to a tool for removing and replacing cardboard disks such as 10 used for closing milk bottles and the like.

One of the objects of the invention is to provide a simple form of tool which is cheap to manufacture and which can be readily 15 thrust into engagement with a cap so that, upon pulling on the tool, the cap will be removed from the bottle and will remain in position on the tool whereby, when it is desired to replace the cap, the tool can be used 20 for this purpose, means being provided for automatically disengaging the cap from the tool when said tool is moved to releasing position.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

In the accompanying drawings the preferred form of the invention has been shown. 35

In said drawings:-

Figure 1 is a view partly in elevation and partly in section of the tool, the parts being shown in their normal positions.

Fig. 2 is a bottom plan view thereof.

Fig. 3 is a side elevation showing the relative positions of the parts when the tool is thrust into engagement with the cap in a milk bottle.

Referring to the figures by characters of reference 1 designates a concavo-convex disk constituting the base of the tool, this disk having a central opening 2 in which a stem 3 is slidably mounted. Formed upon the lower end of the stem is an arrow head 4 having sharp edges and the other end of the stem merges into an eye 5 constituting a handle. A disk 6 is secured to the stem 3 near the eye 5 and constitutes a seat for one

end of a coiled spring 7. This spring extends around the stem 3 and bears at its other end against the base 1.

When it is desired to use the tool for the purpose of removing a disk D from the neck of a bottle B, the disk 1, which is equal to or less than the diameter of the cap or disk D is placed on said disk D, after which the stem 3 is thrust downwardly. This will cause the head 4 to pass through the disk D and will also cause the spring 7 to be placed under compression. By giving the stem 3 a one-quarter turn, the arrow head 4 will be rotated under the disk or cap D so as thus to prevent its withdrawal through the perforation formed by the arrow head. By pulling on the eye or handle 5, the disk or cap D can be withdrawn from the neck of the bottle B and said disk or cap D will obviously remain in position on the tool, it being clamped between the arrow head 4 and the base or disk 1. When it is desired to replace the cap or disk D within the bottle neck B, the said disk D is forced upon its seat and stem 3 is then given a one-quarter turn so as to return the arrow head 4 into register with the perforation formed thereby in the disk or cap D. By then releasing the pressure on the stem 3, the spring 7 will force the disk 6 upwardly, and thus cause the stem 3 to pull the arrow head through the perforation in the cap or disk D. Thus the cap or disk D will remain upon its seat and will be freed from the tool. It will be noted that the spring 7 is so shaped that its end convolutions constitute seats for engagement with the base 1 and the disk 6 respectively. Thus the spring, which is constantly under compression, maintains the stem 3 normally perpendicular and, after the base 1 has been placed on a cap to be removed, it is merely necessary to force the stem downwardly in order to drive the head 4 through the disk D. By then turning the head 4 the spring 7 when released will bind the head upwardly against the disk D. The disk D and the base 1 are thus pressed tightly together and can be removed as one body from the milk bottle or jar and can be as readily replaced in the neck of the bottle.

What is claimed is:-

A tool for removing and replacing the disk closures for milk bottles and the like, including a rod formed with a handle at one

end, an annular flange on the rod adjacent the handle, a concavo-convex member slideable and rotatable on the rod, an attenuated head formed on the rod at that end remote 5 from the handle and having upwardly facing shoulders, and a compression spring surrounding the rod and confined between the flange and the concavo-convex member.

In testimony that I claim the foregoing as my own, I have hereto affixed my signature in the presence of two witnesses. 10

ALEXANDER F. DEMORY.
